UNITED STATES PATENT OFFICE.

ROBERT C. HOPKINS, OF ALLIANCE, OHIO.

OIL BURNER.

Application filed January 13, 1925. Serial No. 2,061.

This invention relates to burners of the class wherein oil is mixed with a blast of air so as to be discharged and burned in combustible mixture therewith.

5 The objects of the invention are to provide a burner of this character in which the nozzle is surrounded by an annular chamber to which oil is supplied, the oil being thus pre-heated and discharged from the annular 10 chamber through nipples, into the nozzle and in the path of an air blast, whereby the oil is atomized and mixed with the air and discharged from the nozzle in a combustible mixture; to provide an adjustable ring within 15 the nozzle for controlling the flame; to provide a shut-off arranged to automatically cover the nozzle to shield the same when the burner is turned off; and to generally improve and simplify a burner of this type.

20 The above and other objects may be attained by constructing the burner in the manner illustrated in the accompanying drawing, in which,

Figure 1 is a longitudinal sectional view 25 through a burner embodying the invention;

Fig. 2, a section on the line 2—2, Fig. 1;

Fig. 3, a section on the line 3—3, Fig. 1, and

Fig. 4, a rear end elevation of the burner.

Similar numerals of reference indicate 30 corresponding parts throughout the drawing.

A T shaped hollow casting is shown at 1 and provided with the central outlet 2 communicating with the air inlet pipe 3 through which air under pressure is admitted to the 35 burner. One end of the casting may be closed as by the threaded plug 4, and the opposite end is provided with the threaded opening 5 in which is located the threaded extremity of the tubular casing 6 and the 40 threaded valve seat 7. The tube 6 and valve seat 7 may be thus adjusted within the threaded opening 5 and tightened therein, one of said members serving as a jam nut to prevent accidental displacement of both members.

The discharge nozzle 8 of the burner is provided with a sleeve 9 fitting upon the outer extremity of the tubular casing 6, and an annular oil reservoir or chamber 10 surrounds the nozzle whereby the oil is pre-heated by the flame. Oil is supplied to the reservoir 10 as by the oil pipe 11, and is conveyed to the nozzle by means of the radially disposed nipples or jets 12, the ends of which 55 are preferably beveled rearwardly as shown at 13.

The oil reservoir is provided with threaded openings 12^a, aligned with the nipples 12, and normally closed by the threaded plugs 12^b. When the burner is in use it can easily 60 be cleaned by removing these plugs and rodding out the obstruction with a wire.

For the purpose of controlling the flame, as by controlling the velocity and location of passage of air through the nozzle, a ring 65 valve 14, of triangular cross sectional shape, is mounted for longitudinal adjustment within the nozzle adjacent the nipples 12 as shown in Fig. 3, and the nozzle side of the opening in the ring 14 being smaller than the air blast 70 side of the nozzle. This ring may be adjusted by the stem 15, connected to the ring as by the yoke 16 and provided with the threaded portion 17 extended through a threaded aperture 18 in the bracket 19, a 75 knob 20 being provided upon the rear end of the stem for rotating the same to project the ring against the inner tapered wall of the nozzle as shown in Fig. 1, whereby the air blast is reduced to the interior diameter of 80 the ring, or to withdraw the ring rearwardly whereby air may pass around the outside of the ring also.

The blast gate 21 for regulating the supply of air may be in the form of a disk having a 85 central opening 22 to accommodate the stem 15, and carried upon a blast gate adjusting rod 23 slidably mounted through the plug 4 and bracket 19, the rear extremity thereof being bent at an angle and located transversely through the sleeve 24 which is slidably supported at one side of the burner as by the bracket 25.

A rod 26 is rotatably mounted in a bearing 27 formed at one side of the nozzle and slidably extended into the sleeve 24, a radial pin 27 upon said rod being located through the spiral slot 28 in the sleeve. A shut-off, in the form of a disk 29, is fixed to the forward end of the rod 26 and arranged to be located 90 in front of the nozzle when the blast gate 21 is in the closed position, as shown in Fig. 1.

In operating the burner the sleeve 24 is pulled rearwardly and, through the rod 23, the blast gate 21 is opened permitting the 105 blast of air to pass through the nozzle. As the sleeve 24 is moved in this direction the pin 27, upon the rod 26, riding in the spiral slot 28 of the sleeve will cause the rod 26 to rotate upon its axis, swinging the shut-off 110 29 away from the nozzle. The oil supply is of course independently controlled, and when

the oil is turned on the reservoir 10 will be filled, pre-heating the oil from the heat of the flame, the pre-heated oil being discharged through the nipple 13 into the blast of air, the oil being atomized and mixed with the air in the nozzle and being discharged therefrom in a combustible mixture.

The flame may be controlled by adjusting the ring 14 within the nozzle to increase or decrease the air passage.

The shut-off 29 is especially adapted for use where burners are provided at opposite sides of a furnace. If only one burner is operating it will be seen that the shut-off 15 upon the burner not in operation prevents the products of combustion from being forced into the same, thus maintaining the interior of the burner free from carbon and the like.

I claim:

- 20 1. A burner including a tubular casing having a nozzle at one end, a valve within the casing, a sliding rod connected to the valve, a sleeve connected to the rod and provided with a spiral slot, a rod rotatably mounted within the sleeve and having a pin located in said slot and a shut-off carried by the rotatable rod and arranged to be moved in front of the nozzle by the closing of said valve.
- 25 2. An oil burner including a tubular casing, an air inlet at one end portion of the casing, a discharge nozzle at the other end portion of the casing, an annular oil pre-heating chamber surrounding the discharge nozzle, an oil supply for the burner communicating with the pre-heating chamber, a ring valve controlling the velocity and location of passage of air through the nozzle, there being a central opening in the ring valve for the passage of air therethrough, means exterior of the casing for longitudinally adjusting the position of the ring valve within the nozzle, a nipple communicating with the pre-heating chamber and opening adjacent the ring valve, whereby air passing through the central opening in the ring valve will atomize the oil discharged from the nipple, a blast gate for regulating the supply of air, and means for adjusting the blast gate.
- 30 35 40 45 50

3. An oil burner including a tubular casing, an air inlet at one end portion of the casing, a discharge nozzle at the other end portion of the casing, an annular oil pre-heating chamber surrounding the discharge nozzle, an oil supply for the burner communicating with the pre-heating chamber, a ring valve triangular in cross section controlling the velocity and location of passage of air blast through the nozzle, there being a central opening in the ring valve for the passage of air therethrough, the nozzle side of the opening being smaller than the air blast side of the opening, means exterior of the casing for longitudinally adjusting the position of the ring valve within the nozzle, a radially disposed nipple communicating with the pre-heating chamber and opening adjacent the ring valve, the end of said nipple being beveled rearwardly, whereby air passing through the central opening in the ring valve will atomize the oil discharged from the nipple, a blast gate for regulating the supply of air, and means for adjusting the blast gate.

4. An oil burner including a tubular casing, an air inlet at one end portion of the casing, a discharge nozzle at the other end portion of the casing, an annular oil pre-heating chamber surrounding the discharge nozzle, an oil supply for the burner communicating with the pre-heating chamber, a ring valve controlling the velocity and location of passage of air through the nozzle, there being a central opening in the ring valve for the passage of air therethrough, means exterior of the casing for longitudinally adjusting the position of the ring valve within the nozzle, a nipple communicating with the pre-heating chamber and opening adjacent the ring valve, whereby air passing through the central opening in the ring valve will atomize the oil discharged from the nipple, a blast gate for regulating the supply of air, a shut-off supported adjacent to the nozzle, and means co-ordinating the closing of the blast gate and the projecting of the shut-off in front of the nozzle.

In testimony that I claim the above, I have hereunto subscribed my name.

ROBT. C. HOPKINS.
